United States Patent Office

Des. 232,564
Patented Aug. 27, 1974

232,564

DOG DISH

Claud W. Kissin, Fort Lee, N.J., assignor to The Hartz Mountain Corporation, Harrison, N.J.

Filed Sept. 1, 1972, Ser. No. 285,893

Term of patent 14 years

Int. Cl. D30—03
U.S. Cl. D30—16

FIG. 1

FIG. 2

FIG. 3

FIG. 4

FIG. 6

FIG. 5

FIG. 7

FIG. 8

FIG. 9

FIG. 10

FIG. 12

FIG. 11

FIG. 1 is a top perspective view of the dog dish showing my new design;

FIG. 2 is a bottom perspective view thereof;

FIG. 3 is a top plan view;

FIG. 4 is a bottom plan view;

FIG. 5 is a side elevational view;

FIG. 6 is a front elevational view;

FIG. 7 is a top perspective view of a modified form of the dog dish, wherein two compartments are provided;

FIG. 8 is a bottom perspective view thereof;

FIG. 9 is a top plan view thereof;

FIG. 10 is a bottom plan view;

FIG. 11 is a side elevational view; and

FIG. 12 is a front elevational view.

I claim:

The ornamental design for a dog dish, as shown and described.
